CONTAINER

Alva F. Gluck, Minerva, Ohio, assignor to The
Minerva Wax Paper Company, Minerva, Ohio,
a corporation of Ohio

Application February 24, 1931, Serial No. 517,761

7 Claims. (Cl. 242—55.5)

This invention relates to dispensing containers for paper rolls and is particularly adapted for household use in dispensing wax paper.

It is among the objects of my invention to 5 provide a dispensing container which will enclose the paper roll and keep it clean, free from dust and other foreign matter. A further object is to provide a container wherein the free edge or end of the paper roll may be readily 10 grasped so that the paper can be easily withdrawn from the container. A further object is to provide a container adapted to be secured to a wall surface such container having a partially opened bottom to permit ready access 15 to the free end of the paper and having a downwardly facing cutting edge along which desired lengths of paper may be torn after having been withdrawn from the container.

Further objects include the provision of a 20 container which on one hand will completely enclose the roll of wax paper and thereby keep it clean and which on the other hand is constructed with ample space adjacent the free edge of the paper as it rests within the general 25 confines of the container so that it may be easily grasped for withdrawal therefrom. Another object is to provide a container which will be strong and durable which may be readily loaded with a new roll and which may be economically 30 manufactured. Another object is to provide a container which will be pleasing in appearance and which may harmoniously conform to the surroundings in which it is to be used.

Other objects more or less ancillary to the 35 foregoing and the manner in which all the various objects are realized will appear in the following, which, considered in conjunction with the accompanying drawing, sets forth the preferred embodiment of the invention.

40 Figure 1 is a front elevation of the improved container with the roll of sheet material therein and showing the means of attaching the same to the wall.

Figure 2 is an end elevation.

45 Figure 3 is a section taken on the plane through the line 3—3 of Fig. 1.

Figure 4 is a perspective of one end of the container.

Referring to the drawing, the numeral 10 50 designates generally a dispensing container constructed in accordance with this invention. The container is constructed preferably of sheet metal and includes a front wall 11 having integral end walls 12 extending rear- 55 wardly therefrom and terminating in mounting

ears on the like 13 disposed parallel to the front wall and adapted to receive screws or other suitable means for supporting the dispensing container on a wall or other surface. The front wall 11 adjacent its lower edge is offset 60 forwardly to provide a suitable cutting edge 14. The offset portion of the front wall allows the free end of the paper to be more easily grasped so that it may be readily withdrawn from the container. Furthermore, the flared portion materially reinforces the front wall. The side walls 12 of the container are preferably notched as at 5 and the forward portion of the topmost edge of the side wall, and the top edge of the front wall are preferably turned inwardly or 70 beaded to present a finished edge.

Upstanding ears 16 formed integrally with the end walls are rounded and punched at 17 to provide bearing surfaces which receive extended lug portions 26 of the top 25 of the 75 container. The lowermost portion of each end walls have an angular portion 29 turned inwardly at right angles to the wall, which serves as a supporting member for the bottom of the container.

The rear wall 18 and bottom 19 are formed integrally with each other. The rear wall has mounting ears 20 of complementary configuration with the ears 13. The ears 13 and 20 are secured together by hollow rivets 21 which are 85 adapted to receive the means for securing the container to the supporting wall. The top edge of the rear wall is offset inwardly and beaded to form a finished edge 22 upon which the top of the container is adapted to rest in open position. This edge 22 is also adapted to restrict the outward movement of the top 25 when in open position. The bottom 19 is adapted to be supported and rest upon the inturned lower edges 29 of the end walls as at 30. The forward portion 31 of the bottom wall is adapted to be angulated upwardly to provide a retaining and centering wall for the roll of paper being dispensed.

The top 25 is preferably pivotally mounted in 100 the upper rear columns of the end walls. The embodiment illustrated shows the rear edge of the cover provided with laterally projecting lugs 26 which pivotally bear in the apertures 17 formed in the ears 16. The edges of the top 105 having depending portions 27 which are adapted to be disposed over the end and front walls of the body of the container when the top thereof is in closed position.

After the container has been secured to the 110

supporting surface, the roll of sheet material may be placed therein by raising the cover 25 and resting the roll upon the bottom surface where it is cradled between the sloping portions 5 thereof. The roll is positioned with the free end of the sheet passing downwardly between the angulated portion 31 of the bottom wall and the inner face of the front wall. Due to the downward slope of the bottom wall, the roll 10 is normally maintained against the portion 31 and thus centered within the container at all times.

The positioning of the roll by the configuration of the bottom wall as shown, keeps the paper out of contact with the front and rear walls and still provides enough frictional resistance to withdrawal of the paper to facilitate tearing the sheet along the cutting edge. The configuration of the bottom wall is such that the 15 axis of the rolls does not move appreciably while an ordinary length of paper is being withdrawn whereby the free edge of the paper is not withdrawn back into the container after a part has been torn along the cutting edge.

20 There is shown in dotted lines at 40 and 41 in Fig. 3 the arc through which the leading edge of the paper will swing after tearing and the position which the leading edge will normally assume. It will be noted that ample space 25 is provided behind the cutting edge, which as noted above, is advanced forwardly of the plane of the body of the front wall on one hand and in front of and below the upturned part 31 of the bottom on the other hand.

30 Furthermore, the leading edge would be a bit below the cutting edge and of course, adequately behind it that the thumb and forefingers may readily grasp the leading edge of the paper and withdraw a sheet of any desired length from the 35 container.

The whole container comprises only three 40 separate pieces plus the four hollow rivets which hold the parts together. The front and end walls and attaching ears 13 along with the bearings for the journals of the lid and the inturned bottom supporting portions are formed in one 45 piece. The back and bottom along with the attaching ears 20 are formed of another piece and the lid with the integrally formed lugs, constituting journals for its pivotal support, are 50 formed in another piece. The simplicity of this construction lends itself both to economy of manufacture, ease of assembly, durability and ease of operation.

55 Although the foregoing description is necessarily of a detailed character in order to set forth completely this invention, it is to be understood that the specific terminology is not intended to be restrictive nor confining and it is 60 further understood that various re-arrangements of parts and modifications of structural detail may be resorted to without departing from the scope or spirit of the invention as herein claimed.

65 I claim:

1. A dispensing container for a paper roll comprising a front wall and integrally formed end walls, the bottom part of the front wall including a cutting edge, a rear wall having a bottom wall integrally formed therewith, said bottom wall being inclined downwardly from the rear to a point spaced away from said cutting edge and thence inclined upwardly toward the front wall and terminating in a region above 75 the cutting edge and spaced away from the

front wall, said end walls having inturned lips extending inwardly and forming a support for said bottom wall.

2. A dispensing container for a paper roll having end walls with integrally formed inturned lips, a cutting edge, a bottom wall adapted to be supported by said inturned lips, said bottom wall being inclined downwardly from the rear to a point spaced away from said cutting edge and thence inclined upwardly toward the front wall and terminating in a region above the cutting edge and spaced away from the front wall, a rear wall formed integrally with said bottom wall and means for securing said end walls and said rear walls together. 80

3. A dispensing container for a paper roll having end walls with integrally formed inturned lips, a bottom wall adapted to be supported by said inturned lips, a rear wall formed integrally with said bottom wall and means for securing said end walls and said rear walls together, said means adapted to receive means for securing said container to a supporting surface. 85

4. A dispensing container for a paper roll having a front wall with its bottom part forming a downwardly directed cutting edge disposed forwardly of the plane of the body thereof, said container having a bottom wall inclined downwardly from the rear to a point spaced away from said cutting edge and thence inclined upwardly toward the front wall and terminating in a region above the cutting edge and spaced away from the front wall, whereby space is provided in which to easily grasp the leading edge of the paper roll. 100

5. A dispensing container for a paper roll having integrally formed front and end walls, integrally formed bottom and rear walls and a lid having longitudinally extending tangs at its rear edge for pivotal support, said rear walls having longitudinally extending tabs with eyelets for receiving attaching screws, said end walls having inturned lips supporting said bottom wall and longitudinally extending tabs 115 matching the said tabs of the rear wall and secured thereto and having eyelets matching the said eyelets in the said tabs of the said rear wall and having upwardly extending apertured ears adjacent the rear wall for pivotally receiving the said tangs of said lid. 120

6. A dispensing container for a paper roll having a front wall, and walls formed integrally therewith, a bottom wall, a rear wall formed integrally with said bottom wall, and means for securing said end walls and said rear wall together, said means being adapted to receive means for securing said container to a supporting surface. 130

7. A dispensing container for a paper roll having a front wall, a rear wall, a bottom wall formed integrally with said rear wall, end walls with integrally formed inturned lips for supporting said bottom wall, means on said bottom wall for centering said roll within said container, said bottom wall terminating a substantial distance away from said front wall and above the bottom edge thereof, said container being open adjacent said front wall longitudinally of its bottom throughout substantially its 145 entire length whereby the free end of the paper can be readily grasped and withdrawn therefrom. 135
